Patented Sept. 26, 1916.

UNITED STATES PATENT OFFICE.

FREDERICK G. SIMPSON, OF SEATTLE, WASHINGTON.

TRANSMITTING APPARATUS FOR WIRELESS-TELEGRAPH STATIONS.

1,199,213.

Specification of Letters Patent. Patented Sept. 26, 1916.

Application filed November 29, 1915. Serial No. 64,180.

To all whom it may concern:

Be it known that I, FREDERICK G. SIMPSON, citizen of the United States, residing at Seattle, in the county of King and State 5 of Washington, have invented a certain new and useful Improvement in Transmitting Apparatus for Wireless-Telegraph Stations, of which the following is a specification.

My invention relates to improvements in 10 transmitting apparatus of wireless telegraph stations and its particular object is to provide means in combination with certain electric circuits which include a condenser and an adjustable spark-gap, where- 15 by, upon the discharge of said condenser through said spark-gap then no resultant oscillations can take place in that one of said circuits within which said spark-gap is included. I accomplish this object by devices 20 which I have illustrated diagrammatically in the accompanying drawing, wherein—

1 designates an electric generator of alternating currents, which generator 1 is provided with terminal contact brushes 2 and 25 3, and from the brush 2 extends a conductor 4 which connects with one terminal of a telegraph key 5 from whose other terminal extends a conductor 6 that connects with one terminal of the primary coil 7 of 30 a transformer 8 the other terminal of said primary coil being connected to the terminal brush 3 by a conductor 9.

The secondary coil 10 of the transformer 8 has one of its terminals connected by a 35 conductor 11 with the anode 12 of a mercury valve 13, of well known form, the cathode 14 of said mercury valve 13 being connected by a conductor 15 with one terminal of a resistance coil 16 whose other 40 terminal is connected by a wire 17 to the earth 18.

The mercury valve 13 contains a quantity 45 of mercury within its lower end portion, indicated by broken lines 19, which mercury constitutes a part of cathode 14 and said mercury valve 13 is provided with an auxiliary anode 20 which is connected by conductor 21 to one terminal of a source of electricity, as a battery 22, whose other terminal 50 is connected by a conductor 23 with one terminal of a switch 24, whose other terminal is connected to the conductor 15 at a point between the cathode 14 and the resistance coil 16, whereby is formed a switch-con- 55 trolled local circuit between the anode 20 and the cathode 14.

The other terminal of the secondary coil 10 is connected by a conductor 25 to one end of both of two conductors 26 and 27, the other end of the conductor 26 being connect- 60 ed to one side 28 of a variable condenser 29 whose other side 30 is connected by a conductor 31 to the conductor 17 at a point thereon between the resistance coil 16 and the earth 18, while the other end of the conductor 27 is connected to the outer end 32 of a spiral conductor 33 whose inner terminal 34 is connected to one terminal of a va- 65 riiable inductance 35, whose other terminal is connected with an antenna 36. 70

An adjustable spark-gap 37 is disposed with one of its terminals connected with the conductor 31 while its other terminal is connected by a conductor 39 to the anode 40 of a mercury valve 41 whose cathode terminal 42 is connected at a point 38 on the outermost convolution of the spiral conductor 33. 75

The mercury valve 41 is in all respects like the mercury valve 13, being provided with an auxiliary anode 43 which is connected to one terminal of a source of electricity, as a battery 44, whose other terminal is connected to one terminal of a circuit breaking switch 45 whose other terminal is connected by a conductor 46 with the cathode ter- 80 minal 42. 85

The operation of the apparatus when ar- 90 ranged as illustrated and described is as follows: The switches 24 and 45 are each moved to a closed position and thereupon the mercury valves 13 and 41 are tilted side- 95 wise in a direction to cause the mercury contained therein to make connection with their respective anodes 20 and 43 thus complet- 100 ing the circuit through their respective bat- 105 teries 22 and 44 to their respective cathode terminals 14 and 42, through which circuits current of the respective one their batteries 22 and 44 may flow, and thereupon said mercury valves 13 and 41 are moved back to perpendicular positions to cause such cur- 110 rents to establish electric arcs between the anode 20 and the cathode 14 and between the anode 43 and the cathode 42, thus, in a well known manner, to prime said mercury valves 13 and 41 whereby electrical impulses from the secondary coil 10 may find pas- 115 sageway through the mercury valve 13 from its anode 12 to its cathode 14 and whereby electrical discharges from the condenser 29 that jump the spark-gap 37 may find pass- 120 way through the mercury valve 41 from its

- anode 40 to its cathode 42. The mercury valves 12 and 41 having been thus primed, a manipulation of a telegraph key 5 will cause the alternating current of the generator 1 to effect the primary coil 7 of the transformer 8 whereby successive groups of electrical impulses will be generated in the secondary coil 10 of said transformer 8, of which electrical impulses only those of a like polarity can be communicated to the conductor 31 to charge the condenser 29 by reason of the interposition of the mercury valve 13, and it is therefore apparent that charges can be communicated to said condenser 29 only during the period of one half of a cycle comprising two successive electrical impulses generated by the generator 1 each of which two impulses is of a different polarity.
- 20 The time required to charge the condenser 29 to a voltage sufficient to break down the spark-gap 37, with which it is connected as shown, depends upon its capacity and the amount of resistance and inductance of the charging circuit and when it becomes charged to such degree as will break down said spark-gap 37, then it will discharge in the direction from the side 30 through the spark-gap 37, thence through the mercury valve 41 to the point 38 on the spiral conductor 33, thence through a portion of the outer convolution of said spiral conductor 33 to the conductor 27, thence through the conductor 26 to the side 28 of said condenser 29, and such discharge will be only a single impulse that again will charge the condenser 29 in a direction to reverse its polarity.
- In the circuit comprising the condenser 29, the conductors 26 and 27, a portion only of the outer convolution of the spiral 33, the mercury valve 41 the spark-gap 37 and a portion of the conductor 31, the amount of capacity in proportion to the amount of inductance is extremely large the resistance of such circuit (which I call the trigger circuit or discharge circuit) being mostly situated in the spark-gap 37 and mercury valve 41.
- 25 It is a well known fact that in circuits where the ratio of capacity to inductance is large, and where a condenser is permitted to discharge through a spark-gap, the tendency of such discharge is to create oscillations which at first are relatively of high amplitude but which rapidly decrease in amplitude and are therefore few in number, and thus when the spark-gap 37 is properly adjusted then in said trigger circuit there would be no current in a direction that is the reverse of the discharge current of said condenser 29, even without the presence of the mercury valve 41 in said trigger circuit, which fact is also partly due to the fact that the circuit comprising
- said condenser 29, conductors 26 and 27, the whole of the spiral conductor 33, the variable inductance 35, the antenna 36, earth 18, a portion of the conductor 17 and the conductor 21 constitutes an oscillating circuit 70 wherein oscillations may have great persistency; and, contemplating the antenna 36 and earth 18, jointly, as constituting a condenser in series with condenser 29, the second half of any oscillation starting from 75 condenser 29 will be directed through said oscillating circuit, and subsequent oscillations derived therefrom will persist within that circuit and not pass across the spark-gap 37 always provided said spark-gap is 80 properly adjusted, since there can be no persisting arc between the electrodes of said spark-gap 37 by reason of the action of the mercury valve 13, the current therethrough being at zero at the moment of the discharge of the condenser 29, and, therefore, the voltage, derived from such current, between the electrodes of the spark-gap 37 is also zero; and the mercury valve 13 also prevents the condenser 29 from discharging 90 any energy back through the secondary coil 10 of the transformer 8. But if the spark-gap 37 be not properly and accurately adjusted, and there be no mercury valve 41 in said trigger circuit as shown, then current impulses in a direction that is the reverse of the discharge current of said condenser 29 might occur in said trigger circuit, and to prevent current impulses in such direction is the object of my present 95 invention and such prevention is effected by the presence of the mercury valve 41 in said trigger circuit, which mercury valve 41 permits the passage therethrough of current impulses coming only in the direction from 100 the side 30 of the condenser 29 to and through the spark-gap 37 as such condenser 29 is discharged, and therefore a proper adjustment of the distance between the electrodes of the spark-gap 37 becomes unnecessary and oscillations in the trigger circuit cannot take place, irrespective of the adjustment or non-adjustment of the spark-gap 37.
- 105 It is true that at the instant of the initial discharge of the condenser 29 through the spark-gap 37 there is also a discharge in the same direction from the earth 18 through said spark-gap 37, the inner convolution of the spiral conductor 33, inductance 35 and antenna 36, but in such latter circuit the ratio of capacity to inductance is so very small that oscillations would have a tendency to persist therein were it not for the mercury valve 41.
- 110 A waste of energy of the initial discharge of the condenser 29 is prevented by the inductive relation between that portion of the outermost convolution of the spiral conductor 33 and the remaining convolutions of said 115
- 120
- 125
- 130

spiral conductor 33, said portion of such outermost convolution forming a part of the circuit which includes the conductors 27 and 26 together with the condenser 29 and spark-gap 37, (which circuit I have hereinbefore termed the trigger circuit) while the remaining convolutions of said spiral conductor 33 form a part of the circuit which I have hereinbefore termed the oscillating circuit and which oscillating circuit includes the whole of the spiral conductor 33, the inductance 35, the antenna 36, earth 18, a part of the conductor 17, the conductor 31, the condenser 29, and conductors 26 and 27. Such inductive relation between said trigger circuit and said oscillating circuit is not absolutely necessary but it improves the efficiency of the apparatus. After a period of time the condenser 29 will be charged anew and the same cycle of operations will be repeated, the extent of such period of time being dependent upon the capacity of the condenser 29, the amount of resistance of the coil 16, the amount of the resistance of the mercury valve 13, and the amount of other resistance in the charging circuit together with the inductance distributed through said charging circuit including the inductances of the secondary coil 10 of the transformer 8. Intelligible signals may be formed in the usual way by a manipulation of the telegraph key 5 which signals will be emitted in the usual manner from the antenna 36 in the form of groups of electromagnetic wave trains, which groups of electromagnetic wave trains may sufficiently effect any detector of the commonly used types that may be employed in the receiving apparatus of a distant wireless telegraph station, and

nothing of the nature of a "heterodyne" or "tikker" is required in such distant wireless telegraph station.

What I claim is:

1. Transmitting apparatus for wireless telegraph stations, which embodies an oscillation circuit within which is included a condenser, the whole of a spiral conductor, a variable inductance, and an antenna in connection with the earth; and a trigger circuit associated with said oscillating circuit, within which trigger circuit is included that part of said oscillating circuit containing said condenser and a portion of said spiral conductor, together with a rectifying valve and a spark-gap. 55
2. Transmitting apparatus for wireless telegraph stations, which embodies a key-controlled source of electricity; a charging circuit associated with said source of electricity, which charging circuit includes a rectifying valve; an oscillating circuit connected to said charging circuit, which oscillating circuit includes a condenser, the whole of a spiral conductor, a variable inductance and a grounded antenna; and a trigger circuit associated with said oscillating circuit, within which trigger circuit is included that part of said oscillating circuit containing said condenser and a portion of said spiral conductor, together with a rectifying valve and a spark-gap. 60

In witness whereof, I hereunto subscribe my name this 22nd day of November, A. D. 1915.

FREDERICK G. SIMPSON.
